UNITED STATES PATENT OFFICE.

THOMAS F. COTE, OF WINNIPEG, MANITOBA, CANADA.

FUSE-PLUG.

1,381,803.

Specification of Letters Patent. Patented June 14, 1921.

Application filed May 28, 1919. Serial No. 300,268.

To all whom it may concern:

Be it known that I, THOMAS F. COTE, a subject of the King of Great Britain, residing at Winnipeg, in the Province of Manitoba and Dominion of Canada, have invented certain new and useful Improvements in Fuse-Plugs; and I do hereby declare the following to be a full, clear, and exact description of the invention, such as will enable others skilled in the art to which it appertains to make and use the same.

This invention relates to new and useful improvements in fuse plugs of the type having removable fuse members and has for one of its objects the provision of a closure for the body which will tightly secure one end of the fuse member to a contact and which will seal the body thereby preventing the escape of flame from the body when the fuse member is blown out and also retards the escape of gases created by the blowing out of the fuse member.

Another object of this invention is the provision of means for preventing the flames from melting or affecting the solder which secures one end of the fuse member to the central contact, thus reducing the quantity of gas in the body when the fuse member is blown.

30 A further object of this invention is the provision of means whereby the central contact may detachably secure one end of the fuse member in place in the body and which permits of said fuse member being removed in case of damage thereto.

A still further object of this invention is the provision of a fuse plug of the above stated character, which shall be simple, durable and efficient, and which may be manufactured and sold at a comparatively low cost.

With these and other objects in view as will become more apparent as the description proceeds, the invention consists in certain novel features of construction, combination, and arrangement of parts as will be hereinafter more fully described and claimed.

For a complete understanding of my invention, reference is to be had to the following description and accompanying drawing in which,

Figure 1 is a vertical sectional view of a fuse plug constructed in accordance with my invention,

Fig. 2 is a vertical sectional view of the

central contact illustrating the means of securing one end of the fuse member thereto,

Fig. 3 is a vertical sectional view illustrating a modified form of my invention in which the fuse member is separate from the central contact and held within the body by said contact.

Fig. 4 is a detail view illustrating the enlarged end of my modified form of fuse element.

Referring in detail to the drawing, the numeral 1 indicates as an entirety a fuse plug consisting of a body 2 having a reduced screw threaded portion 3 on which is threaded a metal ferrule 4 having screw threads on its outer face for co-operation with the usual screw threads within an electric socket. The reduced extension 3 is closed by a disk 5 having an opening 6 to permit a fuse member 7 to extend upwardly within the body. The body 2 is constructed of any desired insulating material which is of a non-breakable nature. The disk 5 is provided with a flange 10 that is engaged by a flange 11 formed upon the metal ferrule 4 for retaining the disk against the extension 3. A gage disk 12 is located within the opening 6 of the disk 5 and is provided with a slot of a given size to permit a fuse member of a given gage to be inserted within the body. It will therefore be seen that the slot in the gage disk 12 will prevent an oversize fuse member being placed within the body.

A central contact plug 13 is provided with a cylindrical portion 14 that fits within the opening 6 in the disk 5 and has one end of the fuse member 7 soldered or otherwise secured therein. After the end of the fuse member 7 has been soldered to the plug 13, the cylindrical portion 14 is filled with plaster of Paris or similar material 15 to form an insulator for preventing the flame when the fuse member 7 blows out from melting or destroying the solder, thus reducing the amount of gases within the body when the fuse member is blown. The cylindrical portion 14 frictionally engages the wall of the opening 6 of the disk 5 so that one end of the fuse member 7 is firmly anchored within the body.

The reduced portion 3 of the body 2 is provided with an opening 16 to permit a contact member 17 to extend through said reduced portion 3 and be soldered or otherwise secured to the metal ferrule 4. The contact member 17 extends upwardly with-

in the body 2 and within a groove 18 and has its upper end angularly related to form a clamp 19 under which is adapted to be positioned the free end of the fuse member 7. 5 A closure plug 20 is threaded into the enlarged end of the body 2 for efficiently sealing said body and also engages the clamping end 19 of the conducting member 17 for forcing the same against the free end 10 of the fuse member 7. It will be noted that when the plug 20 is threaded against the clamping end 19 that the free end of the fuse member 7 will be tightly held between said clamping member and the body 2 of the 15 fuse plug. The opening 16 within the reduced portion 3 of the body 2 will permit any gases that may accumulate within the body from the blowing of the fuse 7 to gradually escape from said body. It is also 20 to be noted that the solder used for securing the fuse member to the central contact plug and also the solder employed to secure the contact member 17 to the metal ferrule is entirely protected from the flame 25 caused by the blowing of the fuse 7, thus reducing the amount of gas within the body, otherwise a considerable amount of gas would be created if the solder was exposed to the flame. It will be further noted that 30 the plug 20 threading into the body 2 efficiently seals the body and prevents the flame from escaping from the body when the fuse member 17 is blown and which can be readily removed from the body when it is 35 desired to replace the fuse member 7 by another fuse member. The plug 20 is provided with a slot 21 to receive a screw driver or like tool for threading the plug into and out of the body. 40 Referring to my modified form of invention, one end of the fuse member 7 is enlarged as illustrated at 22 and disposed to overlie one face of the gage disk 12 and is held against the same by means of a screw 45 threaded contact plug 24 threaded into the

opening 6 of the disk 5, thus it will be seen that the fuse 7 can be readily detached from the body by removing the plug 24.

While I have shown and described the preferred embodiment of my invention, it 50 will be understood that minor changes in construction, combination, and arrangement of parts may be made without departing from the spirit and scope of the invention as claimed. 55

Having thus described my invention, what I claim is:—

1. A fuse plug comprising a body having each end open, a closure plug closing one end of the body, a disk engaging the other 60 end of the body and having a centrally arranged opening and an annular shoulder, a ferrule secured to the body and engaging said shoulder, a gage disk in said opening and having a portion thereof spaced from 65 the wall of said opening to provide a fuse receiving slot, a fuse extending through the slot and into the body, means connecting the fuse to the ferrule, and a plug secured in the opening and forcing one end of the fuse 70 against the gage disk.

2. A fuse plug including a body having a ferrule, an insulating disk secured to the body by said ferrule and having an opening, a gage disk located within the opening of 75 the first named disk, a fuse member extending between the gage disk and the wall of the opening and having an enlarged end disposed against one face of said gage disk, a contact plug threaded within the opening of 80 the first named disk against the end of the fuse member, and means connecting the other end of the fuse member to the ferrule.

In testimony whereof I affix my signature in presence of a witness.

THOMAS F. COTE.

Witness:

BENNETT S. JONES.
